STRIP REWINDING MEANS

Chris A. Christoff, San Gabriel, Calif., assignor
to Clary Multiplier Corporation, San Gabriel,
Calif., a corporation of California

Application December 18, 1950, Serial No. 201,418

5 Claims. (Cl. 242—55)

1

This invention relates to calculating listing machines, adding listing machines, cash register listing machines and the like and has particular reference to paper takeup devices for such machines wherein a paper strip having values recorded thereon by the machine is wound upon a rewind roll and periodically removed for accounting or record purposes.

In order to facilitate removal of such a roll when a capacity diameter is reached, or for other reasons, the roll is usually wound on a flanged mandrel which is removably mounted for rotation in the machine and is rotatably driven by some driving part of the machine mechanism.

In connection with cash registering machines where, for example, a line of customers may be waiting on the cashier, it is of utmost importance that the paper rewind roll be quickly and readily removable and replaceable with the least amount of effort or waste of time and with the least amount of dismantling or handling of parts. Also, when installing the rewind mandrel, the paper attached thereto is usually loose and must generally be wound up manually on the mandrel to remove any sagging or looping before operation of the machine can commence.

Although the provision of a quickly removable and replaceable paper rewind mandrel is a necessary attribute to a cash register machine, it is also a desirable feature when used for rewinding tally rolls and the like for adding listing, bookkeeping and other forms of business machines where the tape must be retained after values are recorded thereon.

It therefore becomes a principal object of the invention to facilitate removal and replacement of a paper rewind mandrel for a machine of the above type.

Another object is to facilitate removal of a roll of paper from a rewind mandrel on which the paper is wound.

Another object is to provide a coupling device for driving a paper rewind mandrel which is automatic in its coupling action.

Another object is to provide a coupling device for a paper rewind mandrel which is rendered ineffective upon withdrawal of the mandrel and which is again rendered effective upon operation of the drive means for the mandrel.

A still further object is to provide a simple device of the foregoing type which is economical to manufacture and which has no parts which must be removed from the machine, other than the mandrel itself, in order to remove a rewind roll.

The manner in which the above and other ob-

2

jects of the invention are accomplished will be readily understood on reference to the following specification when read in conjunction with the accompanying drawings, wherein:

5 Fig. 1 is a longitudinal sectional view through a part of a cash register machine embodying the present invention.

Fig. 2 is a sectional view, similar to that of Fig. 1, illustrating the platen advancing means.

10 Fig. 3 is an exploded perspective view of the paper takeup mandrel and the drive coupling means therefor.

Fig. 4 is a plan view of the paper feed mechanism, with the machine covers removed, and is 15 taken substantially along the line 4—4 of Fig. 1.

Fig. 5 is a plan view, similar to Fig. 4, with parts removed and with the coupling device in uncoupling position.

The invention is herein disclosed as embodied 20 in the well known commercially available Clary cash register machine, Model 303, which is disclosed and claimed generally in the copending application of V. S. Golemon, S. N. 103,468, filed July 7, 1949. Various operating instrumentalities 25 of the machine, particularly of the computing section, are disclosed and claimed in the copending applications of R. E. Boyden, S. N. 582,553, filed March 13, 1945, now U. S. Patent No. 2,583,810, and the copending application of Boyden et al., S. N. 38,294, filed July 12, 1948, now U. S. Patent No. 2,607,526.

It should be understood, however, that although the invention is disclosed in connection with, and particularly applicable to cash registering machines it may equally well be applied to other forms of business machines of the recording or listing type.

The machine in general comprises a computing section (not shown) enclosed by a plastic 40 cover partly indicated at 361 and a cash drawer section enclosed by a cover, part of which is indicated at 11, underlying the computing section.

A rear cover 113 is removably attached to the machine to permit access to the paper tape to 45 install or remove the supply and takeup rolls. The cover 113 is held in place on the cover 361 at its upper end by a pair of locating pins, one of which is indicated at 119, fixed thereon and extending into openings in the cover 361.

The lower end of the cover 113 is provided with tabs, one of which is shown at 122, extending into openings in the cash drawer cover 11 and held in place by a slideable lock 180 which serves to removably lock the cover 113 in place.

55 Amounts entered into the machine or totaled

therefrom are recorded on a pair of superimposed paper tapes or strips 12 and 13, as the latter pass over a platen 18, at a printing station P. The latter strips are supplied in double wound form from a supply roll 15 rotatably mounted at 16 in the rear of the cash drawer section. The strips are fed in superimposed relation over a stationary guide 17 extending integrally from the cash drawer cover 11. The strips are guided over the lower edge of an opening 25 in the cover 361 and then extend under a takeup roll 33 and around the platen 18 against which they are held by a pressure roller 19. Adjacent the printing station the inner tape 13 passes directly over the surface of the platen 18 whereas the outer tape 12 passes between two strands 20 and 21 of an inked printing ribbon. Above the printing station, the tapes are again superimposed and extend through an opening 24 formed in the cover 361.

As disclosed in detail in the aforementioned Boyden application, S. N. 582,553, the printing mechanism comprises a series of printer type wheels 135 carried in side by side relation independent of each other on individual arms 136. The latter are loosely keyed on a printer control shaft 137. Springs 138 tend to rock the arms 136 clockwise to cause the type wheels 135 to strike the superimposed strands of printing ribbon and paper tapes at the printing station. However, the arms are normally retained in the position shown by the shaft 137 until the printing phase of the machine cycle at which time the shaft is rocked clockwise by suitable mechanism (not shown) under control of a drive shaft 51 to allow the printer arms 136 to follow under the action of their springs 138 and thus cause the type wheels 135 to print the values registered thereon.

Registration of the dials is effected through the usual actuator rack mechanism (not shown), each rack being entrained with an idler gear 141 rotatably mounted on a cross shaft 142. The gear 141 is normally in mesh with a pinion 140 rotatably mounted on the associated printer arm 136 when the arms are held in their positions illustrated in Fig. 1. The pinion 140 is maintained in permanent mesh with a gear 139 integral with the associated type wheel 135.

The printing mechanism is mounted in a manner not shown on a printer frame comprising a pair of laterally spaced frame plates 27 and 28 suitably supported in the main machine frame.

Means are provided for intermittently rotating the platen 18 whereby to advance the superimposed tape upwardly a spaced increment during each operation of the machine and after the printing operation. As shown in Fig. 2, a ratchet 302 is integrally attached to the platen 18 and is fed by the upper ear of a pawl 303 pivotally connected at 304 to a cam follower 305. The latter is pivoted on a cross shaft 31 and carries a roller 306 engageable with a cam 307 keyed on the drive shaft 51. The cam follower 305 is held in engagement with the cam 307 by a tension spring 308 extending between the pawl 303 and a lever 309 which for the purpose of the present disclosure may be considered as permanently located in its position illustrated in Fig. 2. The spring 308 is also effective to urge the pawl 303 to the left against a guide pin 311 fastened on the arm 309.

A centralizer arm 316 is pivoted on a frame pin 315 and is urged clockwise by a spring 317 to press a roller 318 thereon against the teeth of the ratchet 302 to locate the platen in its dif-

ferent advanced positions. A suitable tear off or paper severing bar (not shown) is provided to sever the outer tape 12 above the platen whenever desired. The severed tape may thus be issued for example to a customer as a receipt of a purchase while the inner tape is retained for reference or accounting purposes.

The tape 13 is passed over the top of the cover 361, under the forward edge of the rear cover 113, and thereupon it is wound on the rewind roll 30 attached to a rewind mandrel 39. The latter is provided with trunnion journals 31 and 32 journaled in the bottoms of bearing slots 29 formed in the printer frame plates 27 and 28.

Retainers 34 are pivoted on the outer sides of the frame plates 27 and 28 by coaxially located studs 35 and are held in engagement with the journals 31 and 32 of the mandrel by springs 36 extending between the same and suitable stationary parts of the machine. The engaging edges of the retainers are inclined whereby the mandrel may be grasped and drawn laterally along the slots 29 to remove the same, the retainers yielding downwardly during such movement.

The mandrel 39 is driven through a coupling device generally indicated at 38 by a spring belt 39 formed of an endless tension spring wrapped around a pulley 40 forming part of the coupling device 38 and a second pulley 41 integral with the platen 18. The spring belt 39 thus forms a transmission for yieldably rotating the mandrel 39. As shown in Fig. 1 the pulley 41 is larger in diameter than the pulley 40 so as to always tend to drive the mandrel 39 at a higher speed than the platen and thereby maintain the portion of the paper strip extending between the platen 18 and the rewind roll taut regardless of the diameter of the rewind roll.

According to the present invention and in lieu of the usual flanged spool for winding the takeup roll 33, the mandrel 39 is devoid of side flanges for edge guiding the paper tape as it is wound thereon. Thus, when the mandrel with a rewind roll of paper thereon is removed from the machine, the roll may be removed therefrom by merely slipping the same endwise off of the mandrel. In order to edge guide the paper and prevent it from rubbing against the frame plates 27 and 28 and thereby either jamming the mandrel against rotation by the spring belt 39 or creating undue frictional drag on the mandrel, a combined pressure and edge guiding roller 43 is provided having small edge guiding flanges 44 at opposite ends thereof. The roller 43 is mounted on a pair of spaced arms 45 pivoted on a cross shaft 46 to the outer sides of the frame plates 27 and 28. Springs 47 extend between the arms 45 and frame pins 48 to urge the roller 43 against the periphery of the mandrel 39 or the takeup roll 33 wound thereon in order to aid in winding a relatively tight roll on the mandrel and to cause the flanges 44 to extend over the sides of the roll and thereby edge guide the paper as it is wound thereon.

An important feature of the roller construction is that it is loosely pivoted in the arms 45 and that the arms, in turn, are loosely pivoted on the shaft 46, thereby allowing the roller to "float" laterally a slight amount relative to the frame plates 27 and 28. Thus, when starting to wind a roll of paper, the flanges 44 of the roller are centered laterally over the outer ends of the mandrel 39 and as the roll builds up on the mandrel the flanges are guided laterally by the outer convolutions of the paper.

In threading the paper tape through the machine it is inserted in a slit 49 in the mandrel after being passed over the periphery of the roller 43 as shown in Fig. 2. Thus, as the roll is being wound on the mandrel the tension of the paper tape is applied against the roller 43 to aid the light springs 47 in urging the roller against the periphery of the takeup roll, and thereby overcome any tendency of the flanges 44 to climb radially up onto the periphery of the takeup roll. In fact, the springs 47 may be dispensed with, relying solely on the pressure applied thereto by the tape itself to maintain the roller 43 in contact with the periphery of the takeup roll. By edge guiding the paper strip before it reaches the periphery of the rewind roll it may be easily shifted laterally along the periphery of the roller 43 by one or the other of the flanges 44 into proper alignment with the rewind roll and this alignment of the outer convolutions of the rewind roll is thereafter maintained by such flanges.

The coupling device 38 comprises a notched disc 52 integrally secured to the outer extremity of the bearing journal 32 of the mandrel 30. Three triangular notches 53 are formed in the discs 52, any of which is adapted to be engaged by a tooth 54 extending from a disc 55 integral with the pulley 40. The latter is rotatably and slidably mounted on a bearing stud 56 which is attached to an off-board bracket 57, the latter being secured to the printer frame plate 28 by pins 48, 58 and 59 to maintain the stud coaxial with the mandrel 30. A light compression spring 60 extends between the bracket and a cupped element 61, rotatably mounted on the pulley 40. The spring normally urges the pulley into engagement with a head 62 of the stud 56 in which position the driving tooth 54 engages in one or another of the notches 53 to effect a driving connection between the pulley and the mandrel.

It will be noted, on viewing Fig. 5, that the tooth 54 is tapered when viewed from the side. Likewise, each of the notches 53 is generally triangular in shape as viewed in Fig. 1 with one edge extending radially to cooperate with the tooth 54. By virtue of the tapered tooth 54 the mandrel 30 may be withdrawn or replaced in position in the bearing slots in any rotative position thereof and yet be effective to cam the tooth 54 and pulley 40 laterally against the action of spring 60. Should the tooth 54 be in a position extending vertically such as would occur if the tooth were against the radial edge of the lowermost notch shown in Fig. 1, withdrawal of the mandrel would rotate the pulley 40 against the tension of the spring belt 39 until the tooth 54 is rotated sufficiently to present the tapered edge thereof to the notch 53 engaged thereby whereupon the pulley would be cammed laterally as the mandrel is withdrawn.

When threading a tape in the machine and attaching the same to the mandrel by slipping the leading edge of the tape in the slit 49 in the mandrel it is generally necessary to manually rotate the mandrel one or more revolutions to insure attachment of the tape thereof and to remove any sagging or looping of the tape. If the mandrel were coupled to the platen through the spring belt at this time difficulty would be encountered in attempting to rotate the mandrel independently of the platen, since the spring belt would become tensioned on one side and when the mandrel was released the belt would return the

mandrel toward its original position. The present arrangement overcomes this difficulty as follows. Referring to Figs. 4 and 5 in particular, it will be noted that the spring belt 39, which is under tension in order to effect a drive between pulleys 40 and 41, causes a certain amount of friction to exist between the pulley 40 and the bearing stud 56. The tension in the belt 39 relative to the spring 60 is such that when the pulley is cammed or moved laterally into its disengaged position illustrated in Fig. 5, the belt 39 will exert a sufficient amount of frictional engagement between the pulley and the bearing stud to overcome the force of the spring 60 and therefore, as long as the pulley is not rotated, it will be located in its lateral and disengaged position shown in Fig. 5. Thus, the mandrel may be inserted and manually rotated without coupling engagement with the pulley 40. Likewise, if the mandrel were in place and coupled to the pulley, and it were desirable to rotate the mandrel ahead of the pulley, such rotation would cause the converging edges of the engaged triangular slot 53 to cam the pulley tooth 54 laterally into uncoupled position where it would be held by spring belt 39 as indicated in Fig. 5.

However, when the machine is operated, or the platen 18 otherwise rotated in a clockwise direction, the static friction existing between the pulley 40 and the bearing stud 56 is overcome and the spring 60 will then become effective to again return the pulley unit into coupling engagement with the mandrel 30.

Means are provided to manually rotate the platen 18 independently of the machine whenever it is desired to feed the paper tape a greater amount than that fed by the pawl 303, such as generally desired upon completion of the transaction and prior to severing of the tape 12 for use as a customer's receipt. For this purpose, the platen is provided with a hub 65 and a reduced portion 68 on which is rotatably mounted a gear 67 having a hub 66 of slightly larger diameter than the hub 65 and located directly adjacent thereto. A drive spring 69 is fitted over and frictionally engages the hubs 65 and 68, the spring frictionally gripping the hub 68 to a considerably greater extent than it grips the hub 65. Rotation of the gear 67 in a direction tending to unwind the spring will cause the latter to merely slip over the hub 65. However, rotation of the gear in the reverse direction tends to tighten the spring causing it to grip the hub 65 and thus drive the platen therewith. Therefore, the spring forms a one-way drive between the gear and the platen. In order to prevent catching of a coil of the spring 69 between the adjacent ends of the hubs 65 and 68, one coil of the spring is inclined as shown at 70 in Fig. 4 to extend across the ends of the hubs at an appreciable angle.

In order to provide manual actuation of the gear 67 an actuating lever 71 is pivotally mounted on a frame stud 72 and is normally urged by a spring 73 into the position shown in Fig. 1. The lever has a gear sector 74 integrally attached thereto and arranged in permanent mesh with the gear 67. A finger piece 75 is integrally formed on the upper end of the lever 71 and extends through a slot 76 in the machine cover permitting the lever to be moved rearward by the operator against the action of spring 73 to advance the platen.

Although I have described my invention in detail and have therefore used certain terms and languages herein, it is to be understood that the

present disclosure is illustrative rather than restrictive particularly in regard to the make and type of machine to which it is applied and that changes and modifications may be made without departing from the spirit or scope of the invention as set forth in the claims appended hereto.

Having thus described the invention, what I desire to secure by United States Letters Patent is:

1. In a recording machine, the combination with a mandrel for rolling a strip thereon, and means rotatably supporting said mandrel, of a drive element for said mandrel, a shaft supporting said drive element for rotation coaxially of said mandrel and for axial movement relative to said mandrel, coupling means on said drive element and on said mandrel for transmitting a drive therebetween, a spring for urging said drive element toward said mandrel whereby to enable said coupling means, spring means for urging said drive element against one side of said shaft, said spring means being effective to create sufficient friction between said drive element and said shaft to prevent axial movement of said drive element by said spring while said drive element is at rest but ineffective to prevent axial movement of said drive element while said drive element is rotating.

2. In a recording machine, the combination with a mandrel for rolling paper thereon, and means for rotatably supporting said mandrel, of a drive element engageable with said mandrel, means supporting said drive element for rotation coaxially of said mandrel and for movement axially relative to said mandrel and into and out of engagement with said mandrel, a first spring for urging said drive element toward engagement with said mandrel, a second spring for urging said drive element against said supporting means whereby to create frictional engagement therewith, said second spring being sufficient to prevent axial movement of said drive element by said first spring when said drive element is at rest but insufficient to prevent movement of said drive element by said first spring when said drive element is rotating.

3. In a recording machine, the combination with a mandrel for rolling paper thereon, and spaced frames having open slots, each of said slots being closed at one end thereof to form a bearing for rotatably supporting said mandrel, of a drive element engageable with said mandrel, a shaft supporting said drive element for rotation coaxially of said mandrel and for movement axially of said mandrel into and out of driving engagement therewith, a spring for urging said drive element toward engagement with said mandrel, the engaging portions of said drive element and said mandrel being formed to move said drive element along said shaft and against the action of said spring upon movement of said

5 mandrel along said slots, and means for rendering said spring ineffective to move said drive element toward said mandrel when said drive element is at rest and for rendering said spring effective to move said drive element when said drive element is rotating.

4. In a recording machine, the combination with a mandrel for rolling paper thereon and spaced frames having slots therein, each of said 10 slots being closed at one end thereof to form a bearing for rotatably supporting said mandrel, of a shaft extending coaxially of said mandrel, a pulley rotatably mounted on said shaft and movable axially thereof into and out of driving engagement with said mandrel, a spring for urging said pulley toward engagement with said mandrel, means comprising a belt extending over said pulley for rotating said pulley, said belt being under sufficient tension to prevent movement of said pulley along said shaft by said spring when said pulley is at rest and ineffective to prevent movement of said pulley by said spring when said pulley is rotated.

5. In a recording machine, the combination 25 with a mandrel for rolling a strip thereon, and a pair of spaced frames, each of said frames having a slot therein closed at one end thereof to form a bearing for rotatably supporting said mandrel, said slots permitting withdrawal and replacement of said mandrel in said bearings, of a shaft extending coaxially of said mandrel, a first pulley rotatably mounted on said shaft and movable longitudinally therealong into and out of driving engagement with said mandrel, a second pulley, means for rotating said second pulley, an elastic belt extending over said pulleys and adapted to transmit rotation therebetween, a spring for urging said first pulley toward driving engagement with said mandrel, said elastic belt being under sufficient tension to prevent movement of said first pulley along said shaft by said spring when said first pulley is at rest and ineffective to prevent movement of said first pulley by said spring when said first pulley is rotated by said belt, and cooperating means on 30 said first pulley and on said mandrel operable to move said first pulley out of driving engagement with said mandrel upon movement of said mandrel along said slots.

50 45 CHRIS A. CHRISTOFF.
